UNITED STATES PATENT OFFICE.

ROBERT M. KEYES, OF WEST ALLIS, WISCONSIN.

MOTOR.

1,193,397.

Specification of Letters Patent.

Patented Aug. 1, 1916.

Application filed August 19, 1915. Serial No. 46,318.

To all whom it may concern:

Be it known that I, ROBERT M. KEYES, a citizen of the United States, residing at West Allis, in the county of Milwaukee and State of Wisconsin, have invented certain new and useful Improvements in Motors; and I do hereby declare the following to be a full, clear, and exact description of the invention, such as will enable others skilled in the art to which it appertains to make and use the same.

This invention relates to motors, and more particularly to a motor adapted for attachment to row boats, or the like, and the primary object of the invention is to provide a motor, which includes an internal combustion engine, the explosion chamber of which is submerged within the water, so as to provide for the efficient cooling of the motor, eliminating the necessity of the employment of a water pump, mechanism for operating the pump, and for a water jacket surrounding the explosive chamber of the engine.

Another object of this invention is to construct a motor as specified, so that the entire motor and the boat propeller, which is associated therewith, can be turned completely around, by means of the starting and steering handle, thus making it possible to reverse the direction of travel of the boat without stopping, slowing down, or changing the direction of rotation of the engine and propeller.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of the improved motor, showing the same applied to the rear end of a boat, and further showing parts of the motor construction broken away, and Fig. 2 is a fragmentary edge view of the motor. Fig. 3 is a fragmentary side elevation of the steering post of the motor. Fig. 4 is a sectional view on the line 4—4 of Fig. 1.

Referring more particularly to the draw-

ings 1 designates the rear end of a row boat or analogous boat structure, which has an up-standing board 2 secured to the upper surface of the rear end of the same. The motor structure, generically indicated by the numeral 10, is attached to the boat, by means of a bracket structure 3. The bracket structure 3 includes a substantially U-shaped clamp 4, which extends over the board 2 and is held in firm engagement therewith by means of a tightening bolt 5. An arm 6 is formed upon one leg of the U-shaped member 4, and it has a collar 7 formed thereon. An angled arm 8 extends downwardly along the rear end of the boat from the arm 6, and has a collar 9 secured to the outer surface of its lower angled end. A plate 9^a is formed upon the arm 8, and engages the surface of the rear of the boat, for co-acting with the U-shaped section 4 for securely holding the bracket structure 3 firmly in position against and connected to the rear end of the boat 1. The collars 7 and 9 encompass a vertical housing or cylindrical casing 11.

The post or cylindrical casing 11 has a housing 12 connected to the lower end of the same and extending transversely thereto. The casing 12 has cone-shaped end pieces 13 and 14 connected to its ends, and a crank shaft 15 rotatably journaled therein. The crank shaft 15 has a beveled gear 16 mounted thereon, which meshes with a second beveled gear 17. The beveled gear 17 is a half gear and is mounted on a shaft 18 which extends vertically through the casing 11, and has a steering handle 19 connected to its upper end. The steering handle 19 is composed of two sections 20 and 21, which are pivotally connected at their inner ends, to the upper end of the shaft 18, as is shown at 22, for movement vertically, as is shown in dotted lines in Fig. 1 of the drawings.

The crank shaft 15 has the piston rod 23 connected to the wrist 24 of the crank portion of the same. The piston rod 23 has a piston head 25 mounted thereon, which is slidably mounted within a cylinder 26. The cylinder 26 is supported by the housing 12, and extends upwardly therefrom, and forms the combustion chamber of the motor.

A gasolene or volatile fuel retaining tank 28 is supported by the casing 11, and it has a pipe 29 communicating with the lower end

of the same, and extending a short distance downwardly from the oil retaining tank, exteriorly of the casing 11, after which it is bent inwardly and extends into the casing 11, and downwardly therethrough, to the housing 12. The pipe 29, which feeds the fuel from the tank 28 to the chamber of the cylinder 26, extends a short distance through the housing 12, and upwardly out 10 of the same, communicating with the interior of the cylinder 26, as is shown at 30. Any suitable type of valve mechanism may be utilized for controlling the flow of the fuel into the cylinder 26. A mixer or carburetor 31 is interposed in the section of the pipe 29 which extends downwardly from the tank 28, and outside of the post 11.

The cylinder 26 has a spark plug 31' of ordinary construction, communicating with 20 the upper end of the same, which spark plug is connected, by means of electrical conductors 32, to a magneto 33, which is carried by the casing 11. The wires 32 are insulated by water-proof material, so as to 25 prevent the short circuiting of the device, when the wires extend downwardly through the water in which the boat is positioned. A timing lever 34 is provided for regulating or controlling the sparking of the engine. A casing 35, which is constructed of 30 water-proof material extends over and encompasses the portion of the spark plug 31' which protrudes out of the cylinder 26, so as to prevent water from engaging the spark plug and rendering the same inoperative.

When the improved motor is applied to a row boat or the like, the cylinder 26, and the housing 12 are positioned beneath the surface of the water in which the boat is 40 positioned, so that the water will act as a cooling agent for cooling the cylinder 26 during its operation. The crank shaft 15 has a propeller 36 mounted upon one end of the same, which is rotated by the rotation 45 of the crank shaft 15, for driving the boat 1 through the water. The post or cylindrical casing 11 is rotatably carried by the collars 7 and 9, so that the entire motor may be moved in an arc, for steering the boat 1. The upper end of the post or casing 11 is 50 provided with notches 37, which are positioned diametrically opposite of each other, and are adapted for receiving portions of the sections 20 and 21 of the steering handle 19, for rotating the casing and consequently the housing 12, and the various mechanisms connected to the casing 11 of the housing 12, for controlling the direction 55 of travel of the boat, by varying the angle or position of the entire motor structure.

When it is desired to crank or start the engine, the sections 20 and 21 are moved upwardly into the position indicated in dotted lines in Fig. 1 of the drawings, so that they 60 will be positioned out of the notches 37, and

the shaft 18 is rotated, which rotates the crank shaft 15 and imparts initiative rotation to the propeller 36 and also initiative operation to the piston 25, for starting the motor. The exhaust of the motor passes 70 through an exhaust pipe 38, which extends upwardly through the casing 11 to a position above the upper surface of the water.

From the foregoing description taken in connection with the accompanying drawings 75 the advantages of construction and of the method of operation of the improved motor will be readily apparent to those skilled in the art to which this invention appertains and, while in the foregoing description, the 80 principle of the operation of this invention has been described together with various features of construction, it is to be understood that certain minor features of construction, combination and arrangement of 85 parts may be altered to suit practical conditions, provided such alterations are comprehended within the scope of what is claimed.

What is claimed is:—

1. In a motor for boats, the combination, 90 of a vertical casing, a substantially horizontally positioned housing carried by the lower end of said vertical casing, a crank shaft rotatably supported by said housing, a shaft rotatably carried by said vertical casing, miter gears carried by said crank shaft and said vertical shaft for operatively connecting the shafts for synchronous rotation, a propeller carried by said crank shaft, 95 an internal combustion engine operatively connected to said crank shaft and supported by said housing for submersion within the water upon which the boat is riding, means carried by said vertical casing for controlling the operation of said internal combustion engine, a steering arm carried by the upper end of said vertical shaft and adapted for engagement with said vertical casing for changing the position of said housing and 100 the mechanism carried thereby for steering the boat.

2. In a motor for boats, the combination, 105 of a vertical casing, a substantially horizontally positioned housing carried by the lower end of said vertical casing, a crank shaft rotatably supported by said housing, a shaft rotatably carried by said vertical housing, miter gears carried by said crank shaft and said vertical shaft for operatively 110 connecting the shafts for synchronous rotation, a propeller carried by said crank shaft, an internal combustion engine operatively connected to said crank shaft and supported by said housing for submersion 115 within the water upon which the boat is riding, means carried by said vertical casing for controlling the operation of said internal combustion engine, a steering arm carried by the upper end of said vertical 120

shaft and adapted for engagement with said vertical casing for changing the position of said housing and the mechanism carried thereby for steering the boat, and means 5 connected to said vertical casing for attaching the motor structure to a boat.

In testimony whereof I affix my signature in presence of two witnesses.

ROBERT M. KEYES.
